Primary Examiner — Kelley Donnelly(74) *Attorney, Agent, or Firm* — Law Office of Jeff Williams; J. Oliver Williams(57) **CLAIM**

The ornamental design for a modular oil rack stand, as shown and described.

DESCRIPTION

FIG. 1 is an oblique view of a modular oil rack stand according to the present application.

FIG. 2 is a front view of the modular oil rack stand of FIG. 1.

FIG. 3 is a rear view of the modular oil rack stand of FIG. 1.

FIG. 4 is a right view of the modular oil rack stand of FIG. 1.

FIG. 5 is a left view of the modular oil rack stand of FIG. 1.

FIG. 6 is a top view of the modular oil rack stand of FIG. 1.

FIG. 7 is a bottom view of the modular oil rack stand of FIG. 1.

FIG. 8 is an exploded front perspective view of the modular oil rack stand of FIG. 1; and,

FIG. 9 is an exploded rear perspective view of the modular oil rack stand of FIG. 1.

The broken lines are included for the purpose of illustrating environmental structure and form no part of the claimed design.

1 Claim, 8 Drawing Sheets(56)
